UNITED STATES PATENT OFFICE.

JAMES HARTNESS, OF SPRINGFIELD, VERMONT, ASSIGNOR TO THE JONES & LAMSON MACHINE COMPANY, OF SAME PLACE.

STOCK-FEEDING MECHANISM FOR SCREW-MACHINES.

SPECIFICATION forming part of Letters Patent No. 425,377, dated April 8, 1890.

Application filed October 21, 1889. Serial No. 327,626. (No model.)

To all whom it may concern:

Be it known that I, JAMES HARTNESS, of Springfield, in the county of Windsor and State of Vermont, have invented certain new and useful Improvements in Stock-Feeding Mechanism for Screw-Machines, of which the following is a specification.

This invention has for its object to provide improved means for feeding bars, rods, or wires of polygonal form through the holding-chucks of screw-machines without stopping the rotary motion of said bars, rods, or wires, and without marring or defacing the angles thereof.

To this end the invention consists, mainly, in the combination of a rotary spindle, a head or holder affixed thereto, a normally-loose gear supported by said spindle, feed-rolls within said head, arranged at opposite sides of the axial center of the spindle and head, said rolls being so connected to the heads as to be revolved about said center by the rotation of the head, means for holding and releasing the loose gear, and connections between said gear and the feed-rolls, whereby the feed-rolls are rotated on their own axes when said loose gear is held stationary, their revolving motion causing them to perpetuate the rotation of the bar, rod, or wire, and preventing marring or defacement of the angles thereof.

The invention also consists in certain combinations and details incidental to the combination above set forth, all of which I will now proceed to describe and claim.

In the accompanying drawings, forming a part of this specification, Figure 1 represents a side elevation of the head-stock of a screw-machine provided with my improvements. Fig. 2 represents an end view of the feed-roll-carrying head mounted on the spindle of said head-stock. Fig. 3 represents a side elevation of said head and of a portion of the spindle. Fig. 4 represents an end view of the head with its front plate removed. Fig. 5 represents a section on line 5 5, Fig. 2. Fig. 6 represents a section on line 6 6, Fig. 5. Fig. 7 represents a section on line 7 7, Fig. 1, looking toward the left. Fig. 8 represents a side view of the loose gear shown in section in Fig. 5.

The same letters of reference indicate the same parts in all the figures.

In the drawings, *a* represents the head-stock of a screw-machine, and *b* represents the rotary tubular spindle, which is journaled in bearings in the head-stock and is rotated by power applied in the usual or any suitable manner from a driving-shaft, the common way of applying power to the spindle being by a belt from the driving-shaft running on one of a series of graduated pulleys *c c c*, affixed to the spindle. The spindle is provided at one end with a chuck *d*, having jaws arranged to grasp the stock that is passed through the spindle. By "stock" I mean the bar, rod, or wire from which the screws, bolts, &c., are made. The stock is rotated by the chuck, the latter being attached to and rotating with the spindle, and while it is thus rotated it is presented to the several tools which form the shank of the screw and the screw-threads thereon. The chuck may be of any suitable construction—for example, that shown in Letters Patent No. 412,027, dated October 1, 1889.

The improved stock - feeding mechanism constituting the present invention comprises a chambered head *e*, having a hub or sleeve *e'*, which is placed upon and rigidly attached to the rear end of the spindle *b*, so as to rotate therewith, a pair of feed-rolls *f f*, connected with said head and caused by the rotation of the latter to revolve about the center of rotation of the head, and mechanism for rotating said feed - rolls on their own axes while they are revolving, each feed-roll having therefore a planetary motion, whereby it is enabled to feed the stock while the latter is rotating without slipping upon the stock and without scarring the angles thereof, as they would do if they did not revolve in unison with the rotation of the stock while rotating to feed the stock forward. Each feed-roll is affixed to a shaft *g*, which is journaled in a bearing formed in an arm or carrier *h*. Said carrier is pivoted at one end on a shaft *i*, journaled in bearings in the head *e* and arranged parallel with the spindle *b*. Said shaft has a worm *j*, meshing with a worm-gear *k* on the feed-roll shaft *g*, and a spur-gear *l*, meshing with a gear *m*, which is mounted

loosely on the hub e' of the head e . Means are provided, as hereinafter described, for holding the loose gear m in a fixed position, so that it cannot rotate with the spindle b and head e , and for releasing or loosening said gear to permit it to rotate by frictional contact with the head.

It will be seen that when the gear m is held and prevented from rotating, the spindle b and head e continuing to rotate at the same time, the spur-gears $l l$, which are revolved about the gear m by the rotation of the spindle b and head e , will be rotated and will rotate the worm-shafts $i i$, to which they are affixed, said worm-shafts rotating the shafts $g g$ and the feed-rolls $f f$ thereon, so that said rolls will have a planetary motion—that is, they will be rotated on their axes in addition to being revolved by the rotation of the spindle b and head e . The rotation of the rolls causes them to feed the stock, as will be readily seen. The revolving motion of the feed-rolls coincides with the rotary motion of the stock, so that there is no such relative movement of the surface of the stock upon the peripheries of the rolls as there would be if the rolls were simply rotated on their own axes and not revolved in unison with the rotation of the stock. It will be seen, therefore, that stock of polygonal form in cross-section can be fed without injury to its angles, such as would be caused by the rubbing contact of the rotating stock with the feed-rolls if the feed-rolls did not revolve in unison with the rotation of the stock.

When the gear m is released and allowed to rotate with the head e and spindle b , the feed-rolls continue to revolve about the axis of the spindle and head in unison with the rotation of the stock; but they do not rotate, because there is no independent movement of the spur-gears $l l$ relatively to the loose gear m ; hence the feed-rolls bear idly on the stock.

Any suitable means may be employed for holding and releasing the gear m . I have here shown as the best means of which I am at present aware for this purpose a friction-band o , encircling a sleeve p , affixed to the gear m , and mechanism for tightening or compressing said band upon the sleeve p , and thereby causing it to rigidly hold the gear m .

The band o is connected at one end by a screw q with an arm or bracket r , affixed to the head-stock a , its other end being unattached and provided with an enlargement s , having an inclined surface s' , on which bears the beveled end of a slide t . Said slide is fitted to move in a guide on the arm or bracket r and has a beveled end t' , Fig. 1, which is arranged to be acted on by the correspondingly-beveled end of a slide u , which extends at right angles with the slide t and is fitted to move endwise in guides in the head-stock a . The slide u , when moved in the direction indicated by the arrow in Fig. 1, moves the slide t toward the friction-band and causes the inclined end

of slide t to so act on the inclined surface s' on the face end of the band o as to compress the band upon the sleeve p . When the slide u is moved in the opposite direction, it allows the slide t to move back and release the friction-band.

The slide u may be given the described movements by means of gear-segment v on a rock-shaft w , which is journaled in the head-stock, said segment engaging rack-teeth formed in the slide u . The rock-shaft is provided with a lever x , whereby it may be rocked or partly rotated first in one direction and then in the other.

The rock-shaft w and its lever x are connected by an arm y , affixed to the rock-shaft, and a link z , pivoted to the outer end of said arm, with the lower ends of levers $a' a'$, which are pivoted at b' to a bracket c' on the head-stock and have trundle-rolls f' at their upper ends, which enter a groove g' in the collar h' on the chuck d . Said collar is movable on the chuck-body by means of the rock-shaft w , lever x , link z , and levers a' , and when moved in one direction presses the chuck-jaws inwardly and causes them to grasp the stock. When the collar is moved in the opposite direction, it releases the chuck-jaws and causes the latter to release the stock.

A construction whereby the movement of a sleeve on a chuck-body, as above described, is caused to open and close jaws in said body is shown in Patent No. 412,027, above referred to, although the present improvements are not confined to use with that particular chuck, but may be used with a chuck of any other suitable construction. The release of the chuck-jaws by the sleeve b is produced by the same motion of the rock-shaft w which moves the slide u in the direction required to compress the friction-band and lock the gear m ; hence the stock is released by the chuck-jaws by the same movement that makes the feed-rolls operative.

The invention is not limited to the mechanism above described for locking and releasing the gear m , and said gear may be locked and released by any other suitable mechanism without departing from the spirit of the invention.

The arms or carriers h and the feed-rolls thereon are pressed inwardly by springs $i' i'$, attached to the head or holder e , said springs giving the feed-rolls a yielding pressure on the stock. The force of said springs may be regulated by screws $j' j'$, inserted in the head or holder and bearing on the spring i' , as shown in Figs. 4 and 6.

I claim—

1. The combination of a rotary spindle, a head or holder affixed thereto, a normally-loose gear supported by said spindle, feed-rolls arranged at opposite sides of the axial center of the spindle and head and revolved about said center by the rotation of the spindle and head, means for holding and releasing said loose gear, and connections between

said gear and the feed-rolls, whereby when said gear is held stationary the feed-rolls are rotated on their own axes in addition to their revolving motion, the said feed-rolls 5 being permitted to revolve idly about the axial center of the spindle without rotating on their axes when the said gear is released, as set forth.

2. The combination of a rotary spindle, a 10 head or holder affixed thereto, a normally-loose gear supported by said spindle, spur-gears meshing with said loose gear and affixed to shafts journaled in the head or holder, feed-rolls within the head or holder, connections 15 between said rolls and the spur-gears, and means for locking and releasing said loose gear, whereby when said loose gear is released it rotates with the head and spindle without rotating the spur-gears and feed-rolls, 20 the latter revolving idly about the axial center of the spindle, and when said loose gear is held it rotates said spur-gears and feed-rolls, while the feed-rolls are revolving about the axial center of the spindle, as set forth.

25 3. The combination of a rotary spindle, a head or holder affixed thereto, a normally-loose gear supported by said spindle, spur-gears meshing with said loose gear and affixed to shafts journaled in the head or holder, 30 feed-rolls within the head or holder, connections between said rolls and the spur-gears, a friction-band encircling a sleeve affixed to the loose gear, and means for compressing and releasing said friction-band, and thereby alternately holding and releasing the loose gear, 35 as set forth.

4. The combination of a rotary spindle, a head or holder affixed thereto, a normally-loose gear supported by said spindle, spur-gears meshing with said loose gear and affixed to shafts journaled in the head, worms 40 on said shafts, arms or carriers pivoted on said shafts within the head or holder, and shafts journaled in said carriers, and provided 45 at their outer ends with worm-gears meshing with said worms and at their inner ends with feed-rolls, as set forth.

5. The combination of a rotary spindle, a head or holder affixed thereto, shafts *i i*, journaled in said head and provided with worms 50 *j j*, holders *h h*, pivoted on said shafts, feed-rolls *f f*, affixed to shafts *g g*, journaled in said holders, worm-gears *k k* on said feed-roll shafts, meshing with the worms *j j*, and 55 springs *i' i'*, engaged with said holders and exerting a yielding inward pressure on the feed-rolls, as set forth.

6. The combination of a rotary spindle, a head or holder affixed thereto, a normally-loose gear supported by said spindle and provided with a sleeve *p*, spur-gears meshing with said loose gear and affixed to shafts journaled in said head, feed-rolls within the head, connections between said rolls and the spur-gears, whereby rotary movements may be communicated from the open gears to the rolls, a friction-band encircling the sleeve *p*, and means for compressing and releasing said band, as set forth. 65

7. The combination of a rotary spindle, a head or holder affixed thereto, a normally-loose gear supported by said spindle and provided with a sleeve *p*, feed-rolls within the head, connections, substantially as described, between said feed-rolls and loose gear, whereby the feed-rolls are rotated on their own axes when the said gear is held stationary, a friction-band encircling the sleeve *p* and secured at one end to a fixed support, a slide *t*, arranged to move the free end of said band and thereby compress the same on the sleeve *p*, and means for moving said slide to cause the alternate compression and release of the friction-band, as set forth. 75

8. The combination of a rotary spindle, a head or holder affixed thereto, a normally-loose gear supported by said spindle and provided with a sleeve *p*, feed-rolls within the head, connections, substantially as described, between said feed-rolls and loose gear, whereby the feed-rolls are rotated on their own axes when the said gear is held stationary, a friction-band encircling the sleeve *p* and secured at one end to a fixed support, a slide *t*, arranged to move the free end of said band and thereby compress the same on the sleeve *p*, a slide *u*, arranged to move the slide *t*, a rock-shaft *w*, engaged with the slide *u* to give motion to the latter, a chuck having a jaw opening and closing sleeve *h'*, and connections, substantially as described, between said sleeve and rock-shaft, whereby the friction-band is compressed and the chuck-jaws released by a single movement of the rock-shaft, as set forth. 90 100 105

In testimony whereof I have signed my name to this specification, in the presence of two subscribing witnesses, this 15th day of October, A. D. 1889.

JAMES HARTNESS.
